ARCHERY BOW SIGHT

BACKGROUND OF THE INVENTION

As is known, a professional archer employs a good quality bow and trains himself to shoot the bow by the application of a rigid pattern of events such that extreme accuracy may be accomplished. The professional archer will always nock an arrow at the same point on the bowstring, and draw the string back such that a particular portion of the hand contacts a particular portion of the head. For example, some archers draw the string back so that the tip of the index finger touches the corner of the mouth. In this manner, the feathered end of the arrow is always at substantially the same distance from the eye and there only remains the action of elevating or lowering the lead of the arrow to correspond to the range at which the target is placed. Some archers aim the bow by intuition, while professional archers employ bow sights of various types.

Bow sights are employed to facilitate the sighting or aiming of the bow at different ranges. In all such bow sights, the archer aligns the target with a sighting element which extends from the bow into his line of sight. Depending upon the height of the sighting element above the archer's hand, he will have to raise or lower the point of the arrow in order to align the sighting element with the target. If the sighting element is close to the archer's hand, he will have to elevate the arrow point and increase range in order to align the target with the sighting element. On the other hand, as the sighting element is progressively raised above the archer's hand, he will have to lower the arrow point and shorten range in order to align the target and sighting element. In the past, various types of bow sights have been provided. In one type, normally used for target practice and tournaments, a single sighting element is slideable along the track or bracket extending substantially parallel to the string of the bow. Normally, the track has indicated thereon various positions which correspond to the different ranges through which the arrow is to be shot. Another type, such as that shown in my U.S. Pat. No. 3,310,875, employs a plurality of sighting elements each of which is spaced above the arrow receiving portion of the bow by a different distance. In this arrangement, each sighting element corresponds to a particular range or distance from the bow at which the released arrow will hit the target, the highest sighting element corresponding to the shortest range while the lowest sighting element corresponds to the longest range. This latter type of bow sight is particularly useful for the hunter who, when sighting a target such as a deer, normally does not have the time to slide a sighting element to the position corresponding to the range of the target. In my aforesaid U.S. Pat. No. 3,310,875, I have disclosed a multiple sighting element bow sight wherein each of the sighting elements is normally disposed in a position out of the line of sight of the archer but is movable to a sighting position wherein it extends transversely of the body of the bow and into the line of sight of an archer aiming an arrow. In this manner, the disadvantages of a plurality of sighting elements in the field of view of the archer are eliminated.

One difficulty encountered with prior art bow sights is that the sighting elements are normally positioned on the track or bracket by means of fastening devices such as screws. Accordingly, in order to vary the position of a sighting element, it is necessary to unfasten it from the track or bracket, move it to a new position, and again fasten it to the bracket. It has been found in actual practice that frequent, fine adjustments of the sighting elements are required. For example, a sighting element may be positioned on the bracket for a target range of 50 feet; and this may be accurate for the wind conditions and other circumstances prevailing at the time the sighting element was fixed in position. However, under other wind conditions, prevailing perhaps on a succeeding day, the setting of the sighting element will not be exactly correct for a range of 50 feet. Hence, the archer must manually unfasten the sighting element, move it slightly to compensate for the changed conditions, and again fasten it to the bracket. This is a somewhat

cumbersome and time-consuming operation, but is necessary unless the archer intends to use the bow sight to approximate range only.

SUMMARY OF THE INVENTION

As an overall object, the present invention provides a new and improved archery bow sight in which a sighting element or elements may first be moved into a position on a bracket for an approximate range and thereafter moved into an exact range position by means of a vernier adjustment.

More specifically, an object of the invention is to provide a bow sight of the type described above wherein one or more sighting elements are mounted on a bracket switch, in turn, is 10 threaded on a shaft which can be rotated to move the bracket and one or more sighting elements carried thereon upwardly or downwardly in a vernier adjustment.

A further object of the invention is to provide a screw-type 15 vernier adjustment for an archery bow sight wherein the screw is rotated by means of a knob provided with a spring-loaded ball and detent arrangement such that the knob and screw may be fixed in any one of a plurality of angular positions.

A still further object of the invention is to provide a bow 20 sight having a plurality of sighting elements all provided with a vernier adjustment and capable of being movable into or out of the archer's line of sight for aiming the bow.

In accordance with the invention, a bow sight is provided 25 comprising an elongated member adapted to be secured to the body of a bow above the arrow receiving area thereof and having upper and lower generally parallel flange portions. Extending between the flange portions is a screw device rotatable in bearings provided in the respective flange portions. At least one sighting element carrier is threaded on the screw means, while means are provided for preventing rotation of the carrier as the screw means is rotated whereby the carrier will be moved upwardly or downwardly as the screw means is rotated. In this manner, a fine vernier adjustment of a 30 sighting element carried on the carrier can be effected.

Preferably, the elongated screw is provided at one end with 35 a knob having a spring-loaded ball adapted to fit into detents spaced around the screw such that the screw may be rotated by the knob and held in a selected position by the ball and detent arrangement, thereby preventing inadvertent movement 40 of the carrier and sighting element.

Further, in accordance with the invention, the individual 45 carriers for the sighting elements are held in position by means of permanent magnets. In one embodiment of the invention shown herein, a plurality of carriers and sighting elements is provided, each of the carriers comprising an L-shaped arm threaded on the screw and pivotal about the axis of the screw. Permanent magnet means are provided for maintaining each of the carriers and their associated sighting elements in either a first position out of line of sight of the archer 50 or in a second position wherein the sighting element is in the line of sight of the archer. In this manner, a plurality of vertically spaced sighting elements may be provided which are normally maintained out of the line of sight of the archer. 55 However, any selected one of the carriers and its associated sighting element may be rotated about the screw into a position where it is in the line of sight of the archer and held in its second position by the aforesaid magnet means.

The above and other objects and features of the invention 60 will become apparent from the following detailed description taken in connection with the accompanying drawings which form a part of this specification, and in which:

FIG. 1 is an elevational view of the conventional bow provided with the bow sight of the present invention;

FIG. 2 is an enlarged perspective view of the bow sight of the present invention showing the manner in which it is secured to the bow;

FIG. 3 is a plan view of the bow sight shown in FIG. 2;

FIG. 4 is a cross-sectional view taken along the line IV-IV 65 of FIG. 2;

FIG. 5 is a cross-sectional view taken along the line V-V of FIG. 3;

FIG. 6 illustrates a detachable reticle for a sighting element which can be utilized in accordance with the invention; and

FIG. 7 illustrates an alternative embodiment of the invention wherein a single sighting element is utilized.

With reference now to the drawings, and in particular to FIG. 1, there is illustrated a conventional bow 10 comprising a central body portion 12, a gripping portion 14 beneath the central body portion 12, and a pair of oppositely extending bendable arms 16A and 16B. In the lower region of the central body 12 there is provided an arrow-receiving portion 18 for receiving an arrow 20. Extending between the bendable arms 16A and 16B is a string 22 which, when pulled away from the central body portion 12, serves to bend the bendable arms 16A and 16B to provide the force for propelling the arrow 20. Secured to the side of the central body portion 12 by means of bracket 24 is the bow sight 26 of the present invention.

The bow sight 26 is shown in detail in FIGS. 2 and 3 and includes a plate or arm 28 which fits into the bracket 24 secured to one side of the central body portion 12. Suitable fastening means such as a screw, not shown, may be provided to hold the plate 28 within the bracket 24 and to provide for adjustment of the arm and sight inwardly or outwardly for a particular bowstring position. Secured to the plate 28, as best shown in FIG. 3, is a first elongated member 30. The elongated member 30 has a slot 32 therein which receives a fastening nut and bolt 34. In this manner, the entire bow sight 26 may be adjusted upwardly or downwardly to suit the requirements of a particular bow.

Secured to the top of the elongated member 30 is a first flange member 36. Similarly, a second flange member 38 is carried at the bottom of the elongated member 30. Also extending between the flange members 36 and 38 is a magnet assembly 40. As best shown in FIG. 5, the magnet assembly 40 comprises a permanent magnet 42 in the form of a strip and having north and south poles extending along its opposite edges. The magnet 42 is sandwiched between metallic strips 44 and 46; and the entire magnet assembly 40 is secured to the flange members 36 and 38 by means of screws 48.

Also extending between the flange members 36 and 38 is an elongated screw 48 rotatable in bearings provided in bores extending through the flange members 36 and 38 as perhaps best shown in FIG. 4. Threaded to the top of the screw 48, as best shown in FIG. 4, is a knurled knob 50 having a bore 52 therein which receives a spring-loaded ball bearing assembly 54. The spring-loaded bearing assembly is adapted to cooperate with detents 56 provided in the upper surface of the flange member 36, the arrangement being such that the screw 48 may be rotated by exerting a slight torque on the knob 50; however, at the same time, the knob 50 and screw 48 are held against inadvertent rotation when the spring-loaded ball bearing assembly 54 is in one of the detents 56. As will be understood, any desired number of detents 56 may be provided around the axis of the screw 48, the greater the number of detents, the more accurate and precise is the angular positioning of the screw 48.

Carried on the screw 48 is a plurality of sighting element carriers 58 each comprising an L-shaped arm 60 which carries, at one end thereof, a plate 62. At the other end of each L-shaped arm 60 is a threaded bore which receives a threaded sighting element 64. Each sighting element comprises a threaded portion, tapered portion 66 and a ball sight 68 on the end of the tapered portion 66. The sighting element is held in a locked position by means of a lock nut 70; however, the lock nut may be loosened and the sighting element moved axially toward and away from the carrier 58 by rotating it, thereby providing a means for compensating for windage.

In the bow sight of FIGS. 2 and 3, for example, each of the sighting element carriers 58 is positionable in a sighting position, indicated by the lower carrier of FIG. 2, and in an out position, indicated by the upper carrier of FIG. 2. While in the out position as shown by the upper sighting element of FIG. 2,

the bar 62 on the L-shaped arm 60 engages the rear edge of the magnet assembly 40 and is held securely thereby. However, by a slight torque on the forward end of the arm 60, the sighting element may be rotated into the position shown by the lower element of FIG. 2 where the forward end of the arm 60 engages the other side of the magnet assembly 40 to hold it securely in engagement therewith. In the use of the invention, each of the sighting element carriers 58 will be positioned along the screw 48 to correspond to a specific range. This range can be marked on a strip 72 (FIG. 5) slipped within a carrier 74 secured to the plate 44, for example.

In the practice of the invention, the plate 28 will be initially slipped through the clamp 24 and the plate and bow sight secured to the bow by means of a fastening screw or the like. Thereafter, the archer can test the sight to determine whether the entire bow sight is correctly positioned for the ranges indicated on the strip 72. If the archer should find, for example, that his arrow falls short of 80 feet when aiming with the sighting element intended for a range of 80 feet, he can then loosen the nut 34 and lower the entire sight until the actual range of the arrow is approximately equal to indicated range of the sighting element which he is using. Thereafter, to effect fine adjustments in range, the screw 48 can be rotated by the knob 50, thereby moving all of the sighting element carriers 58 upwardly or downwardly along the screw. If changes in wind direction or other conditions should occur such that the actual range of the arrow does not correspond to that indicated by the sighting element, further adjustments can be made by simply turning the screw 48, the spring-loaded ball 54 serving to maintain the screw at any rotational position to which it is turned. Thus, the screw 48 provides a vernier adjustment for all of the sighting elements of the bow sight.

In FIG. 6, a plastic reticle 76 is shown having an opening 78 adapted to receive the ball sight 68 of an associated sighting element 64. In this manner, the reticle 76 can be snapped onto the ball sight or removed and the ball sight 68 itself employed. As will be understood, however, when the reticle 76 is employed, it will be necessary to lower the entire bow sight assembly 26 in order to compensate for the increased height of the center line of the reticle.

With reference now to FIG. 7, another embodiment of the invention is shown wherein a bow sight 80 is secured to the backside of the central portion 12 of the bow rather than to the side as in the embodiment of FIGS. 1-5. The bow sight 80 includes a generally U-shaped bracket 82 secured to the back of the central portion 12 and having outwardly projecting flange portions 84 and 86. Extending between the flange portions is a screw 88, similar to the screw 48 in FIG. 2, for example. Secured to the upper end of the screw 88, as in the embodiment of FIGS. 1-5, is a knurled knob 90 provided on its underside with a spring-loaded ball and detent arrangement similar to that of the previous embodiment whereby the screw may be easily rotated, but at the same time held at a particular angular position against inadvertent displacement.

Threadedly received on the screw 88 is a second U-shaped member 92 having threaded openings 94 in flanges 96 through which the screw 88 passes. The U-shaped member 92 is magnetized to have north and south poles at its opposite edges. Slideable on the main shank portion of the U-shaped member 92 is a U-shaped member 98 which is held on the member 92 by means of the magnetic lines of flux generated by the permanently magnetized member 92. The member 98, which comprises a sighting element carrier may, however, slide upwardly or downwardly on the main shank portion of the U-shaped member 92 for various ranges which are marked thereon as shown. Carried on the sighting element carrier 98 is a sighting element 100 having a ball sight 102 at its outer extremity.

With the device of FIG. 7, the member 98 is first moved to the mark on member 92 for an approximate range position. Thereafter, the archer may aim at a target having a range of eight feet, for example; and if the arrow falls short of the target, the screw 88 is rotated to lower the U-shaped member 92

and the sighting element 100 carried thereby. On the other hand, if the arrow should overshoot the target, the entire assembly of member 92, member 98 and the sighting element 100 carried thereby are elevated by rotation of the screw 88.

It can be seen, therefore, that the present invention provides a vernier adjustment for bow sights which enables a very fine range adjustment regardless of wind conditions or other circumstances. Although the invention has been shown in connection with certain specific embodiments, it will be readily apparent to those skilled in the art that various changes in form and arrangement of parts may be made to suit requirements without departing from the spirit and scope of the invention.

I claim:

1. In combination with an archery bow having an arrow receiving area thereon, an archery bow sight comprising an elongated member adapted to be secured to the body of said bow above said arrow receiving area thereof and having upper and lower generally parallel flange portions, a screw device extending between the flange portions and rotatable about an axis extending generally parallel to said elongated member, a plurality of sighting element carriers threadedly received on the screw device, each of said carriers having a sighting element secured thereto such that movement of a carrier up or down on said screw device will carry its associated sighting element therewith, means for rotating said screw device and for preventing rotation of said carriers as the screw device is rotated whereby all of said sighting element carriers and the

sighting elements carried thereby will be simultaneously moved upwardly or downwardly along the elongated member as the screw device is rotated, each sighting element being rotatable from a position where it is out of the line of sight of the archer using the bow to a position where it is in the line of sight of the archer, means for releasably holding each of said sighting elements in its position out of the line of sight of the archer, and means for releasably holding each of said sighting elements in its position where it is in the line of sight of the archer.

5 2. The bow sight of claim 1 wherein said means for holding said sighting elements in positions in and out of the line of sight of the archer comprises permanent magnet means for maintaining all of said sighting element carriers in either of said positions.

10 3. The bow sight of claim 2 wherein said permanent magnet means comprises a single permanent magnet, one pole of which engages a sighting element to hold it in one position and the other pole of which engages a sighting element to hold it in 15 the other position.

20 4. The bow sight of claim 1 wherein said screw device is provided at one end with a knob having a spring-loaded ball 25 adapted to fit into detents spaced around the screw in one of said parallel flange portions such that the screw may be rotated by the knob and held in a selected position by the ball and detent arrangement.
